UNITED STATES PATENT OFFICE.

JOHN R. RENFRO, JR., OF VERNON, TEXAS.

DESIGN FOR A CHURN-DASH.

SPECIFICATION forming part of Design No. 28,606, dated May 10, 1898.

Application filed February 10, 1898. Serial No. 669,857. Term of patent 7 years.

To all whom it may concern:

Be it known that I, JOHN R. RENFRO, Jr., of Vernon, in the county of Wilbarger and State of Texas, have invented a certain new and useful Design for a Churn-Dasher; and I do hereby declare the following to be a full, clear, and exact description of the invention, such as will enable others skilled in the art to which it pertains to make and use it, reference being had to the accompanying drawing, which forms part of this specification.

My invention relates to a design for a churn-dasher, which is illustrated in the accompanying perspective view thereof.

The essential feature of my design consists of a hub with two concentric rings *a* and

the inclined wings or blades situated between the inner ring *a* and the hub and between the inner ring *a* and the outer ring *b*, substantially as shown. 20

Having thus described my design, what I claim, and desire to secure by Letters Patent, is—

The design for a churn-dash substantially as herein shown and described. 25

In testimony whereof I affix my signature in presence of two witnesses.

J. R. RENFRO, JR.
